(57) **CLAIM**

The ornamental design for a golf bag top, as shown and described.

DESCRIPTION

FIG. 1 is a perspective view of a golf bag top showing the new design;

FIG. 2 is a top view of the golf bag top shown in FIG. 1;
FIG. 3 is an end view of the golf bag top taken from the
bottom in FIG. 2;

FIG. 4 is an opposite end view of the golf bag top taken from
the top in FIG. 2; and,

FIG. 5 is a side elevation view of the golf bag top taken from
the left in FIG. 3, with the opposite side elevation view taken
from the right in FIG. 3 being a mirror image thereof.
